HAND OPERATED SHARPENING DEVICE

Frederick Ehksam, Oley, Pa.

Application October 15, 1952, Serial No. 314,877

10 Claims. (Cl. 51—204)

1

This invention relates to stone-like, hand held and manipulated sharpening or honing devices, used for sharpening the cutting edges of articles such as knives, axes, machetes, scythes, sickles, cutters, etc., and more particularly concerns a device of this type provided with special handle means so that the device may be safely and efficiently manipulated for best sharpening and other results.

One object of the invention is to provide a 10 novel device of the type indicated.

Another object is to provide such a device which has certain structural and functional features of advantage over the similar prior art devices.

Another object is to provide such a device having means for protecting the fingers of the user against accidental contact with the cutting edge being sharpened with the device.

It is also an object to provide such a device with novel handle means adapted to permit finger protected holding of the device while carrying out the sharpening procedure in the most efficient manner.

A further object is to provide such a device having handle means adapted to readily permit convenient immersion of the device in a cleaning fluid, when desired, so that the entire working surface or surfaces thereof may be kept in condition for best sharpening results.

An additional object is to provide such a device having handle means adapted to permit the device to rotate or move in such manner during the sharpening operation as to effect uniform wear action of the device.

With these and other objects in view, which will become more readily apparent from the following detailed description of the practical and illustrative embodiments of my device shown in the accompanying drawings, the invention comprises the novel implement, the constituent elements thereof, features of construction and arrangement of parts in cooperative relationship, as more particularly defined by the hereto appended claims.

In the accompanying drawings:

Figure 1 is a partial perspective and partial sectional view of one form of my sharpening device, or implement, as it appears when held by the hand during the sharpening of an edge of a cutting blade.

Fig. 1A illustrates, on an enlarged scale, three exemplary cross-sectional configurations of typical cutting edges that may be sharpened with my novel device.

Fig. 2 is a front elevational view of the device shown in Fig. 1.

Fig. 3 is a rear elevational view of the device shown in Fig. 1.

Fig. 4 is a side elevational view of the device shown in Fig. 1.

2

Fig. 5 is a perspective view, similar to Fig. 1, but of a modified form of my sharpening device.

Fig. 6 is a vertical cross-sectional view of the device shown in Fig. 5, taken as indicated by the arrows 6—6 on Fig. 7.

Figs. 7 and 8 are, respectively, front and rear elevational views of the modified form of my device shown in Fig. 5.

Fig. 9 is a cross-sectional view of a modified form of the device.

It will be helpful to an understanding of my invention to first briefly consider some of the more important aspects and phases thereof, so that these may be kept in mind during the subsequent reading of the detailed description of the practical and illustrative embodiments of my novel device as disclosed in the accompanying drawings.

In general, when sharpening an implement 20 with my novel device, such as a machete, axe, scythe, sickle, knife, etc., the blade of the implement is held in such manner that it faces the operator. This is done so that the operator can observe the cutting edge of the implement at all

25 times and note the progress he is making during the sharpening operation. It is well-known that a cutting edge is not sharpened to the fullest extent as long as light is reflected from it. By holding my novel device with the right hand in 30 the manner indicated by Figs. 1 and 5, the operator can clearly observe both the cutting edge of the implement and the effect of the sharpening action thereon.

My novel device can also be utilized for 35 removing burrs from dies, in the same finger protected manner as when sharpening implements, and for other purposes.

The special handle means of my novel sharpening device comprises an elongated flexible cord-like or chain-like element that is formed so that it can be hooked or wound around one or more fingers, as desired, and found most convenient by the operator, for the purpose of more or less firmly drawing the rear of the device against 45 certain fingers and in such manner as to permit the device to have a certain amount of rotational freedom, whereby to effect uniform wear action thereof.

One form of my novel device is provided at the 50 rear thereof with a finger tip protecting recess (see Figs. 1, 3 and 4) to permit the tips of three fingers of the operator's hand to be placed therein so as to guard or protect them against accidental contact with the cutting edge of an implement 55 while it is being sharpened. While so held the stone-like sharpening member of the device may have more or less pressure applied thereto by the fingers so as to permit rotational movement, as desired, for effecting uniform wear of the sharpening surface.

Another form of my novel device is provided

with an elongated flexible handle element adapted to be held so that it will draw the rear face of the device against the ends of two fingers (see Fig. 5), thereby to rotatably support the grinding stone for even wear of the sharpening surface, as before. With this arrangement, the device overhangs the ends of the fingers in order to keep the cutting edge that is being sharpened from accidentally coming in contact with the fingers.

As hereinafter explained, my device may also be provided with a coarse grained working surface and a fine grained working surface (see Figs. 5-8) so that it may be utilized to first rough grind and then finish hone a cutting edge.

In Figs. 1, 2, 3 and 4 of the drawings, my device is shown as comprising a sharpening, or honing stone 1, that is shaped of suitable material, such as single grain, vitrified pure alumina (corundum) and includes a cylindrical body having a rounded edge 2, that surrounds a flat grinding surface 3. The rear end of the cylindrical body of the sharpening stone is recessed to form a cavity or pocket 4 therein. The latter has an outwardly inclined side wall 5, so as to provide a convenient, comfortable and protected location for accommodating the front ends of the thumb and first two fingers of the operator's hand, as clearly shown in Fig. 1. Extending rearwardly and centrally from the grinding surface 3 is a small pocket forming recess 6, that is connected by a central aperture 7 with the pocket 4 formed in the rear section of the stone 1. A handle element or member is provided for holding the stone 1, in the form of a looped flexible cord 9, that is arranged to extend through the aperture 7 and has an anchoring knot 10 at one end thereof located within the pocket 6. As shown, the looped portion of the cord 9 extends rearwardly beyond the pocket 4.

With the parts of my device so arranged, the ring finger of the operator's hand may be engaged in the loop 9^a of the cord 9, to draw the knot 10 against a shoulder 11 formed at the rear of the pocket 6, so as to force the rear of the sharpening stone over the tip of the thumb, index finger, and middle finger of the operator's hand thereby to firmly seat the stone 1 on these fingers for convenient and easy manipulation thereby.

By referring to Fig. 1 it will be apparent that the sharpening stone 1, when held as indicated, can be readily circularly gyrated, or reciprocated in a straight line, or otherwise moved, while held at the proper angle against the side of the cutting edge of a cutting implement, indicated by the letter C in Fig. 1. The cutting edge of the implement C is preferably held so that the cutting edge thereof faces the operator. This will enable the latter to observe the effect of the sharpening action on the cutting edge of the implement C during the sharpening operation until the desired shape and sharpness of the cutting edge has been attained.

The modified form of my device shown in Figs. 5 to 8 inclusive, comprises a sharpening stone of substantially disc-shaped formation which consists of two fixedly united parts or sections 13 and 14. These two parts or sections are respectively formed of a coarse and fine grain of material suitable for carrying out the coarse and fine sharpening work for which this composite stone is intended. For example, the larger part or section 13 is formed of coarse grain pure alumina (corundum) and the smaller part 14 of fine grain pure alumina (corundum), the said

parts being fused together and vitrified. The section 13 is centrally provided with a pocket 15 which extends inwardly from its flat sharpening surface 13^a, and the section 14 is provided with a similar central pocket 16 which extends inwardly from its sharpening surface 14^a. The said pockets 15 and 16 are connected by an aperture 17 of smaller diameter than said pockets so as to provide a shoulder 18 at the inner end of the pocket 15 and a shoulder 19 at the inner end of the pocket 16.

If desired, a washer like metallic insert 20 may be fixedly embedded in the grinding stone between the coarse grain section 13 and fine grain section 14, as illustrated in Fig. 9, thereby to provide shoulders 18^a and 19^a and an aperture 17^a extending from one pocket to the other.

In Fig. 6 there is shown a handle element for the sharpening stone which comprises a flexible metallic chain 21 that is adapted to freely pass through the hole 17. At each of its ends the chain 21 is provided with a small, substantially bell-shaped member 22 and 23 arranged to become anchored when respectively pulled into and seated in the pockets 15 and 16 so that their outwardly flaring end flanges engage or abut the shoulders 18^a or 19^a.

By pulling the flexible chain 21 from one side of the sharpening stone to the other, either one or the other of the members 22 or 23 allows the flexible chain to extend from the sharpening stone so as to provide a handle element that can be wound around a finger, or otherwise held, so that the rear of the grinding stone is against the thumb and index finger of the operator's hand, while the outer ends of these fingers are protectively located within the outer edge of the stone, as illustrated in Fig. 5. When held in this manner, the sharpening stone can be freely manipulated to carry out a sharpening operation involving a circular gyrating motion or a lengthwise reciprocating movement along the cutting edge of the implement C of Fig. 5. During such sharpening operation the stone may also be permitted to partly rotate in connection with each sharpening movement of the stone, so as to effect uniform wear action of the latter. By seating either one or the other of the bell-shaped members 22 or 23 in its respective anchoring position within the stone, the handle element or chain 21 can be utilized for properly holding either the stone section 13 or the stone section 14 in position for effecting a sharpening operation.

The modified form of my device illustrated in section in Fig. 9, comprises a flexible loop forming cord handle element 24 having anchoring members 25 and 26 at each end thereof so that the sharpening stone may be held and manipulated by the insertion of two fingers into the loop and drawing the stone against the tip of the fingers, substantially as illustrated in Fig. 1.

Fig. 1A shows three basic types of cutting edges which can be quickly and easily sharpened by means of my device. The rounded corner of the sharpening stone is used to sharpen the concave, or hollow ground sides of the cutting edge illustrated at the left in this figure, while the flat sharpening faces of the stone are utilized to sharpen either the straight or the convex sides of the cutting edges illustrated respectively in the middle and at the right in Fig. 1A.

It is to be understood that my device is not limited in its use to the sharpening of implements and that it can be used in substantially the same manner as herein indicated for removing

burrs from dies, and for other purposes, to attain similar results.

Of course, the improvements specifically shown and described can be changed and modified in various ways without departing from the invention herein disclosed, the scope of which is more particularly indicated by the hereto appended claims.

I claim:

1. A hand operated sharpening device of the character described comprising in combination, a member provided with a flat working surface at each end thereof, an elongated flexible handle element, anchoring means at each end of said element, and means within said member arranged to receive one or the other of said anchoring means so as to effect extension of the handle element beyond the member in opposite direction to the working surface selected for operation.

2. A hand operated sharpening device of the character described comprising in combination, a member provided with a flat working surface at each end thereof which surfaces differ from each other in their sharpening characteristics, an elongated flexible handle element, anchoring means at each end of said element, and means within said member arranged to receive one or the other of said anchoring means so as to effect extension of the handle element beyond the member in opposite direction to the working surface selected for operation.

3. A hand operated sharpening device of the character described comprising in combination, a member provided with a flat working surface at each end thereof which surface differ from each other in their sharpening characteristics, an elongated flexible loop-forming handle element, anchoring means at each end of said element, and means within said member arranged to receive one or the other of said anchoring means so as to effect extension of the handle element beyond the member in opposite direction to the working surface selected for operation.

4. A hand operated sharpening device of the character described comprising in combination, a substantially cylindrically shaped stone-like member provided with a flat external working surface at one end thereof an elongated flexible handle element, anchoring means at one end of said element, and means on said member arranged to receive said anchoring means so as to effect extension of the handle element beyond said member in opposite direction to said working surface.

5. A hand operated sharpening device of the character described comprising in combination, a substantially cylindrically shaped stone-like member provided with a flat external working surface at one end thereof and a finger tip receiving pocket at the other end thereof, an elongated flexible handle element, anchoring means at one end of said element, and means on the member arranged to receive said anchoring means so as to effect extension of the handle element beyond said stone-like member in opposite direction to said working surface.

6. A hand operated sharpening device of the character described comprising in combination, a substantially cylindrically shaped stone-like member provided with a flat external working surface and a curved working surface at one end

thereof, an elongated flexible handle element, anchoring means at one end of said element, and means within the stone-like member arranged to receive said anchoring means so as to effect extension of the handle element rearwardly beyond said stone-like member.

7. A hand operated sharpening device of the character described comprising in combination, a substantially cylindrically shaped stone-like member provided with a flat external working surface at the front thereof and a finger tip receiving pocket at the rear thereof, an elongated flexible loop-forming handle element, anchoring means at one end of said element, and means located within the stone-like member and arranged to receive said anchoring means so as to effect extension of the handle element rearwardly beyond said stone-like member.

8. A hand operated sharpening device of the character described comprising in combination, a substantially cylindrically shaped stone-like member provided with a flat and a curved working surface at the front thereof and having a finger tip receiving pocket at the rear thereof, an elongated flexible loop-forming handle element, anchoring means at one end of said element, and means located within the cylindrical member and arranged to receive said anchoring means so as to effect extension of the handle element rearwardly beyond said member.

9. A hand operated sharpening device of the character described comprising in combination, a cylindrically shaped stone-like member formed to provide a flat external working surface of coarse grain sharpening material at one end thereof and a flat external working surface of fine grain sharpening material at the other end thereof, an elongated flexible handle element, anchoring means at each end of said handle element, and means located within the stone-like member and arranged to receive one or the other of said anchoring means so as to effect selective extension of the handle element beyond the stone-like member in a direction opposite to said coarse grain surface or said fine grain surface.

10. A hand operated sharpening device of the character described comprising in combination, a cylindrically shaped stone-like member formed to provide a flat and a curved external working surface of coarse grain sharpening material at one end thereof and a flat and a curved external working surface of fine grain sharpening material at the other end thereof, an elongated flexible handle element, anchoring means at each end of said handle element, and means located within the stone-like member and arranged to receive one or the other of said anchoring means so as to effect selective extension of the handle element beyond the stone-like member in a direction opposite to said coarse grain surface or said fine grain surface.
